(57) **CLAIM**

The ornamental design for a garment cage assembly, as shown and described.

DESCRIPTION

FIG. 1 is a perspective view of the garment cage assembly showing my new design;

FIG. 2 is a side view thereof;

FIG. 3 is a top view thereof; and,

FIG. 4 is a bottom view thereof.

The broken lines shown in FIG. 3 are for illustrative purposes only and form no part of the claimed design.
